UNITED STATES PATENT OFFICE

JACOB HANHARDT, OF LARNED, KANSAS

SALT WATER PLUG

Application filed March 31, 1931. Serial No. 526,737.

This invention appertains to new and useful improvements in well apparatus, and more particularly to a salt water plug for eliminating the difficulties occasioned by discharges of salt water from wells located in fields where such subterranean channels are encountered.

The principal object of the invention is to provide a plug for the well casing to prevent the discharge of the salt water from the casing.

Referring to the drawings:—

Figure 1 represents a fragmentary side elevational view of a well casing showing the plug in position.

Fig. 2 represents a vertical sectional view through the structure shown in Fig. 1.

Fig. 3 represents a sectional view taken substantially on the line 3—3 of Fig. 1.

Fig. 4 represents a sectional view taken substantially on the line 4—4 of Fig. 1.

Fig. 5 represents a cross sectional view taken substantially on the line 5—5 of Fig. 1.

Fig. 6 represents a perspective view of one section of the plug.

Referring to the drawings wherein like numerals designate like parts, it can be seen that numeral 5 represents the upper portion of the usual well casing, while numeral 6 represents the deduction pipes.

In carrying out the present invention, a two-part clamp generally referred to by numeral 7, the section of this clamp being flanged as at 8 and secured together by bolts 9 against the upper portion of the casing 5 in the manner substantially shown in Figs. 1 and 2. Each of these sections of the clamp 7 is provided with lugs 10. A follower plate 11 is provided with a central opening 12 through which the eduction pipe 6 extends and this follower plate 11 is provided with openings, and these openings are disposed bolts 13 which also extend through openings in the lugs 10.

The plug which is clearly shown in Figs. 2 and 4 is of a frusto-conical shape and divided into a pair of sections 14—14. These sections 14—14 are engaged against the eduction pipe 6 in the manner substantially shown in Fig. 4 and driven down-

wardly into the casing 5, so that they wedge snugly between the eduction pipe 6 and the casing 5, and may be of lead or hard rubber.

To retain the sections 14—14 thus placed, the follower plate 11 is fed downwardly 66 against the sections of the plug by actuating the nuts 15, on the bolts 16.

While the foregoing specification sets forth the invention in specific terms, it is to be understood that numerous changes in the shape, size and materials may be resorted to without departing from the spirit and scope of the invention as claimed hereinafter.

Having thus described my invention, what I claim as new is:—

A plugging device for interposition between the usual well casing and eduction pipe of a well structure comprising a clamp band divided into a pair of sections, for engagement around the upper edge portion of the well casing, clamping means between the ends of the said band, outwardly extending ears on the band, a packing plug of annular construction and divided into a pair of sections, said plug being tapered longitudinally 70 for wedged disposition into the upper end portion of the casing and against the eduction pipe, a follower plate having a central opening for receiving the eduction pipe, said follower plate being engaged against 75 the upper enlarged end of the plug and provided with openings for receiving bolts, said ears being provided with openings for receiving bolts, bolts disposed through the registering openings of the plate and ears, 80 and nuts engaged on the said bolts.

In testimony whereof I affix my signature.
JACOB HANHARDT.
